[57] CLAIM

The ornamental design for the kitty litter cabinet, as shown and described.

DESCRIPTION

FIG. 1 is a front elevational view of the kitty litter cabinet showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross-sectional view thereof, taken along line 7—7 of FIG. 5, the broken line showing of the litter box for illustrative purposes only and forming no part of the claimed design; and,

FIG. 8 is an upper left perspective view thereof.
